United States Patent Office

Des. 208,266
Patented Aug. 8, 1967

208,266

LUGGAGE LOCK

David Damast, 22-14 40th Ave.,
Long Island City, N.Y. 11101

Filed Dec. 15, 1966, Ser. No. 5,044

Term of patent 3½ years

(Cl. D50—7)

FIG. 2 is a front elevational view thereof,
FIG. 3 is a side elevational view thereof, and
FIG. 4 is a top view thereof.
The dominant features reside in the solid line portions.
I claim:
The ornamental design for a luggage lock, substantially as shown and described.
